ATTORNEYS.

UNITED STATES PATENT OFFICE.

FREDERICK F. CLARKE, OF FRANKLIN, PENNSYLVANIA, ASSIGNOR TO COLBURN MACHINE TOOL COMPANY, OF FRANKLIN, PENNSYLVANIA, A CORPORATION OF PENNSYLVANIA.

CENTER-INDICATING DEVICE.

1,351,504.

Specification of Letters Patent. Patented Aug. 31, 1920.

Application filed April 7, 1919. Serial No. 288,066.

To all whom it may concern:

Be it known that I, FREDERICK F. CLARKE, a citizen of the United States of America, and a resident of Franklin, Pennsylvania, have invented a new and useful Improvement in Center-Indicating Devices, which invention is fully set forth in the following specification.

This invention relates to center-indicating devices for boring and turning mills. In the operation of such mills it is frequently desirable, especially in boring operations, to position the tool socket so that its longitudinal axis is in exact coincidence with the axis of rotation of the table and, while it is possible to bring the tool socket into approximate central position by use of the traversing mechanism and a final adjustment device, it is exceeding difficult to bring the tool socket so that its center line passes exactly through the center of the table unless some indicating mechanism is employed to show when said position is reached. In my Patent No. 1,185,065, granted May 30, 1916, I have disclosed and claimed a center-indicating device for accomplishing this purpose, and my present invention has for an object to provide an improved and simplified construction for accomplishing the same end.

The invention is capable of receiving a variety of mechanical expressions, one of which is shown on the accompanying drawing, but it is to be expressly understood that the drawing is for purposes of illustration only and is not to be construed as a definition of the limits of the invention, reference being had to the appended claims for that purpose.

Referring in detail to said drawing,

Figure 1 is a partial elevation of the saddle and cross-rail of a vertical boring and turning mill and shows a center-indicating device embodying the present invention in its non-center-indicating position.

Fig. 2 is a partial cross-section through the saddle and cross-rail showing the indicating mechanism in side elevation.

Fig. 3 is a front view showing the indicating member in center indicating position, and

Fig. 4 is an enlarged rear view showing the means for normally maintaining the in-

dicating member in non-center-indicating position.

1 designates the saddle, 2 the cross-rail, 3 the ram and 4 the tool socket of a boring and turning mill of any suitable construction. In place of a single tool socket a turret could obviously be employed.

In the form shown the saddle is provided at any suitable position with a slot 5, which may be either straight or arcuate, in which is mounted to slide an indicating member 6 provided with a mark 7 which in one position of the member 6 is designed to register with a mark 8 suitably provided on the saddle. The indicating member 6 is shown as an elongated plate attached to a stem 9 mounted for sliding movement in a slot 10 which extends from the front to the rear of the saddle, at which point the stem 9 is connected to an arm 11 pivotally mounted in a recess 12 provided in the rear face of the saddle. While the arm 11 may be mounted in any suitable way, it is shown as provided with a pin 13 engaged in a socket 14.

To normally maintain the indicating member 6 so that its mark 7 is out of register with the mark 8, means are provided for normally retaining said member at one end of its slot. While said means may be of any suitable construction, the form shown comprises a pin 15, with a reduced portion 16 mounted for reciprocation in a recess 17 provided in the saddle. A coil spring 18 surrounds the reduced portion 16 and, by engagement with the shoulder thereby provided on the pin 15, maintains said pin in engagement with the stem 9 of the indicating member. For convenience in construction and assembly the recess 17 may be provided as an aperture extending from the edge of the saddle to the slot 10, in which case it may be closed by a threaded plug 19.

To operate the indicating member so as to move the mark 7 into register with the mark 8 suitable means are mounted on the cross-rail. In the form shown a pin 20 is provided on the cross rail and is designed to engage the pivoted arm 11 and move the indicating member 6 into center-indicating position, a groove, as illustrated at 21, being provided in the rear face of the saddle for the passage of said pin.

The indicating member is normally main-

tained in the position shown in Fig. 1 by the action of spring 18 (see Fig. 4). As the center line of the tool socket approaches the center of the table, however, pin 20 engages arm 11 and moves member 6 to the left as viewed in Fig. 1, and the construction and arrangement is such that when said center line exactly passes through the center of the table, mark 7 comes into register with mark 8 as shown in Fig. 3.

While the indicating member 6 has been shown as mounted for rectilinear movement, it is apparent that the slots 5 and 10 could be made arcuate about the center 13 without departing from the spirit of this invention. Furthermore, while the indicating member has been shown as mounted on the saddle and its actuating member as mounted on the cross-rail, the arrangement of these parts could be reversed within the purview of this invention. In fact, while the embodiment of the invention illustrated on the drawing has been described with considerable particularity, the invention is not limited thereto for it is capable of receiving a variety of mechanical expressions some of which will readily suggest themselves to those skilled in the art. Reference is therefore to be had to the appended claims for a definition of the limits of the invention.

What is claimed is:

1. A center-indicating device for boring and turning mills comprising a rectilinearly-movable indicating member carried by the saddle of the mill, and means on the cross-rail of said mill for actuating said member to indicate the coincidence of the center line of the tool-socket with the center of the table.
2. A center-indicating device for boring and turning mills comprising a rectilinearly-movable indicating member carried by the saddle of the mill, means on the cross-rail of said mill for actuating said member to indicate the coincidence of the center line of the tool socket with the center of the table, and means normally maintaining said indicating member out of said indicating position.
3. In combination with the saddle and cross rail of a boring and turning mill, a slide indicating member carried by one of said elements and a slidable actuating member carried by the other of said elements, said members coacting to indicate when the center line of the tool socket passes through the center of the table.
4. In combination with the saddle and cross rail of a boring and turning mill, a

slide indicating member carried by one of said elements and a slidable actuating member carried by the other of said elements, said members coacting to indicate when the center line of the tool socket passes through the center of the table, and means normally maintaining said indicating member out of said indicating position.

5. A center-indicating device for boring and turning mills comprising an indicating member slidably mounted on the saddle of the mill, and means on the cross rail of the mill to move said member into center-indicating position when the center line of the tool holder passes through the center of the table.

6. A center-indicating device for boring and turning mills comprising an indicating member mounted on the saddle of the mill and having an arm extending therefrom, and means on the cross rail of the mill for directly operating said arm and thereby said member to indicate when the center line of the tool socket passes through the center of the table.

7. A center-indicating device for a boring and turning mill comprising an indicating member, an arm pivoted on the saddle of said mill and connected to said member, and means on the cross rail of the mill for moving said arm and thereby said member into center-indicating position.

8. A center indicating device for a boring and turning mill comprising an indicating member, an arm pivoted on the saddle of said mill and connected to said member, means for moving said arm and thereby said member into center-indicating position, and a spring normally holding said member out of center-indicating position.

9. In combination with the saddle and cross rail of a boring and turning mill, an arm pivoted on one of said elements, an indicating member connected to said arm, and means on the other of said elements for engaging said arm and moving said indicating member into center-indicating position.

10. In combination with the saddle and cross rail of a boring and turning mill, a rectilinearly-movable indicating member on one of said elements, and means on the other of said elements for moving said member into center-indicating position when the axis of the tool holder coincides with the axis of the table.

In testimony whereof I have signed this specification.

FREDERICK F. CLARKE.
